REFINING OF FATTY OILS

Arthur U. Ayres, Philadelphia, and Frederick H. Smith, Huntingdon Valley, Pa., assignors to The Sharples Corporation, a corporation of Delaware

Application October 12, 1954, Serial No. 461,863

14 Claims. (Cl. 260—425)

This invention pertains to the refining of fatty oils (e. g. glyceride oils), and more particularly to the refining of vegetable and animal oils, such as cottonseed oil, soya bean oil, peanut oil, corn oil, sunflower seed oil, sesame seed oil, rape seed oil, coconut oil, babassu oil, palm oil, palm kernel oil, linseed oil, perilla seed oil, rice bran oil, tallow, lard, grease, fish oil and whale oil. The invention pertains still more particularly to the refining of fatty oils with sodium carbonate.

Fatty oils are ordinarily refined by adding to the oil an aqueous alkaline solution, followed by conditioning or other treatment, and then by separating from the oil the soapstock formed. The purpose of such refining is to neutralize and remove the free fatty acids present, to remove whatever gums may be present, to remove impurities and/or to improve oil color.

Sodium carbonate which is commonly known as soda ash is a desirable reagent for the alkaline refining of fatty oils, since theoretically at least it will not saponify neutral oil in a refining process, and is available in large amounts at low cost.

In the neutralization of fatty acids by means of sodium carbonate, considerable quantities of gaseous carbon dioxide are evolved, the reaction being illustrated by equations as follows:

wherein R is a hydrocarbon radical having for example between 11 and 17 carbon atoms. This formation of carbon dioxide and its presence in the reaction mixture has heretofore been considered to present considerable difficulties in the refining. In any event it has been found impossible to carry the foregoing illustrated neutralization of fatty acids to anywhere near approaching completion when employing a stoichiometric equivalent of sodium carbonate based on free fatty acids, with the result that the amount of sodium carbonate necessary to neutralize the free fatty acids is very considerably in excess of the theoretical stoichiometric quantity, i. e., when considering both sodium ions of sodium carbonate available for neutralization purposes.

A process known in the trade as the "soda ash process" is in large scale commercial use, and involves the addition of an aqueous solution of sodium carbonate to the oil in substantial excess. The resulting mixture cannot be satisfactorily separated under ordinary conditions, since carbon dioxide is evolved in such volume as to interfere with the separation of the soapstock from the oil. In this commercial process this difficulty is overcome by introducing the mixture into a flash chamber while at an elevated temperature and subjecting it to a vacuum therein. The carbon dioxide and the major portion of the water present are thereby removed from the mixture. After the carbon dioxide and water have been removed, the resulting dehydrated mixture is rehydrated by admixing therewith additional aqueous

2

sodium carbonate solution, and thereafter the latter mixture is subjected to separation such as by the use of a centrifuge.

In another method for the refining of fatty oils with aqueous sodium carbonate, the necessity for the use of the aforementioned dehydration and rehydration steps to condition the oil for centrifugal separation is said to be avoided by carrying out the centrifugal separation step at a relatively low temperature, i. e., below 110° F., while maintaining pressure upon the materials being separated in the centrifuge. The low temperatures in conjunction with the imposed pressures are employed to prevent liberation of carbon dioxide prior to and during the centrifugal separation.

15 The losses that occur during the alkaline refining of fatty oils result from:

- (1) The entrainment of neutral fatty oil in the soapstock formed;
- (2) The absorption of neutral fatty oil in the gums which separate along with the soapstock;
- (3) The saponification of neutral fatty oil into soapstock; and
- (4) The emulsification of neutral fatty oil in the soapstock phase.

20 While by the use of the aforesaid commercial process, these losses of neutral fatty oil may be very considerably reduced over the losses which occur when refining fatty oil by the old batch kettle method employing caustic soda, i. e., sodium hydroxide as the refining reagent, there is nevertheless considerable room for improvement. Moreover, these prior art methods employing aqueous sodium carbonate as the refining reagent are complicated in the one case by the necessity of employing dehydration and rehydration steps, and in the other case by the necessity of employing elevated pressures and reduced temperatures.

25 It has also been proposed to use a very large excess of aqueous sodium carbonate, that is, aqueous sodium carbonate in amount at least three times that necessary to neutralize the free fatty acids, e. g., from 5 to 12 times that necessary, in order to avoid upon centrifugation the production of a muddy oil effluent, and a soapstock containing an excessive amount of neutral oil. Since, as pointed out above, the amount necessary to neutralize the free fatty acids is very considerably in excess of the theoretical stoichiometric amount, the amount of sodium carbonate employed in the latter process when expressed as a multiple of the theoretical stoichiometric amount is far greater than the numeral three given as a lower limit.

30 The present invention resides in the discovery that by the employment in combination of (1) relatively high temperatures; (2) relatively concentrated aqueous sodium carbonate solutions; and (3) an appropriate stoichiometric relationship between the sodium carbonate contained in said solutions and the free fatty acid contained in the oil to be refined, not only are the major difficulties inherent in prior processes avoided, permitting manifold simplification of the process steps, but also the losses are markedly reduced. In addition, when a second refining step is employed such as to further reduce color, e. g., by the use of a wash with aqueous caustic soda as is common in the art, a greater reduction in color of the oil usually can be obtained in such re-refining when the initial refining is performed in accordance with this invention, rather than by such prior art processes, particularly in the case of relatively highly colored oils such as expeller cottonseed oil.

35 40 45 50 55 60 65 70 75 80 85 90 95 While the practice of the new process, as above defined, results in outstanding savings in neutral oil over prior art practice, it is found that additional savings may be

effected in most instances, and even better centrifugal separations of soapstock and oil from each other obtained, by venting off from the mixture of oil and reagent after mixing, but before centrifugal separation, at least a portion of any gases, including carbon dioxide, present in the vapor phase under the prevailing conditions.

Further features of the invention will become apparent to persons skilled in the art as the specification proceeds and upon reference to the drawings in which:

Figure 1 is a flow diagram illustrating one adaptation of the invention;

Figure 2 is a flow diagram illustrating another adaptation of the invention; and

Figure 3 is a flow diagram illustrating still another adaptation of the invention.

In Figure 1 of the drawings at 10 is shown a source of fatty oil to be refined. This fatty oil flows through line 11 to mixer 12 wherein it is mixed with aqueous sodium carbonate flowing from source 13. The ratio of aqueous sodium carbonate to fatty oil fed to mixer 12 is controlled by proportioning pumps 14 and 15, or other suitable device or devices.

The mixture of oil and aqueous sodium carbonate flows from mixer 12 through heater 16 wherein the temperature of the mixture is raised. After being heated in heater 16 the mixture flows to centrifuge 17 wherein soapstock is separated from the oil, the soapstock flowing from centrifuge 17 as indicated at 18, and the oil flowing from centrifuge 17 as indicated at 19.

Centrifuge 17 may be of any desired construction for the separation of the phases. It may operate, for example, on the so-called open bowl principle, or it may operate on the so-called full bowl principle.

As is well known, the discharge of the separated phases in the case of an open bowl is over weirs or weir-like devices spaced from the axis of rotation, the heavier phase being discharged at a greater radial distance from the axis than the lighter phase. An air core is formed in the bowl adjacent to the axis of rotation, which preferably is vented, i. e., open to the atmosphere, such as in the case of the centrifuge shown in U. S. Patent 1,634,243, and when so vented, an open bowl is outstandingly adapted to the practice of the invention.

When operating with a full bowl, on the other hand, the bowl is maintained completely full of liquid when in operation, and the discharge of the lighter phase is along the axis of rotation. Since pressure on the feed to the bowl is required to maintain it full of liquid, a seal is necessary between the stationary feed pipe and the rotating bowl. Also, since it is usually necessary to provide a back pressure in one of the discharging streams to obtain the desired position of the interface between the phases in the bowl, it is customary to provide a seal between the stationary discharge pipe for that phase and its outlet on the rotating bowl. Frequently, a seal is also provided between the stationary discharge pipe for the other phase and its outlet on the rotating bowl.

The construction and operation of centrifuges of both the open bowl and full bowl types are well known, and both types are readily available in the trade.

The mixture of oil and reagent in the practice of the invention is brought to a temperature of at least 180° F. prior to separation, and is at a temperature of at least 180° F. at the time of separation. The mixture may be heated to the desired temperature in heater 16 or otherwise, e. g., the oil and/or reagent may be heated in whole or in part prior to mixing, in the case of the oil preferably not much above 110° F. in order to avoid possible fixing of color, particularly in the case of cottonseed oil.

When operating with a bowl of the open type, the mixture is usually heated to between 180° F. and 212° F., although higher temperatures may be employed if desired, such as up to 220° F. or 225° F., particularly when pressure is applied during heating. Elevated pressures may be conveniently applied by inserting a constriction in line

20 leading from heater 16, such as illustrated at 21. The constricted feed orifice ordinarily employed in feeding a bowl of the open type, and positioned, for example, at the end of line 20, serves excellently for the purpose.

6 Feed pressures of from 5 to 20 pounds per square inch gauge are commonly employed. Any vaporization which might possibly occur upon the release of any pressure imposed upon the feed does not interfere with the separation.

10 What has been said with respect to heating the feed mixture when operating with a bowl of the open type applies equally when operating with a bowl of the closed or full bowl type. Since, when operating with a closed bowl it is possible to apply fairly high elevated pressures

15 to the mixture being separated, particularly when appropriate back pressures are applied to the respective discharging streams, fairly high refining temperatures, such as up to 350° F. may be employed. Feed pressures of from 25 to 150 pounds per square inch gauge are illustrative.

20 It is also possible to operate at similar elevated refining temperatures and pressures with a conventional open type centrifuge by surrounding the same with a closed pressure chamber through the walls of which the various inlet and outlet conduits extend, and equalizing the pressure between the closed chamber and closed receiving tanks such as the tanks 22 and 22-a in which the separated materials are collected. Applied pressures are, of course, to avoid undue vaporization at the elevated temperatures employed, such as of the water present.

30 Any desired contact time between oil and reagent may be employed, such as between one minute and thirty minutes, lower contact times being preferred.

The concentration of the aqueous sodium carbonate fed to mixer 12 is at least 22° Bé. It is found that a good 35 working range is between 22° Bé. and 30° Bé. although aqueous sodium carbonate solutions of higher Baumé may be employed, particularly if the aqueous sodium carbonate is maintained at elevated temperature at its source to avoid precipitation of solid sodium carbonate therefrom which preferably is avoided.

40 Whereas in prior processes for the refining of fatty oils with aqueous sodium carbonate, a multiple of the amount necessary to neutralize the free fatty acids present in the oil is employed as the criterion in arriving at the amount of alkaline agent to be employed, it has been discovered that in the practice of the present invention the percentage of free fatty acids in the oil is of major importance, and that such percentage is of necessity the criterion in arriving at an appropriate ratio of reagent to oil to be employed to obtain outstandingly low losses. In the practice of the present invention the amount of sodium carbonate employed for refining is from 2 to 3 times the theoretical stoichiometric amount for the particular oil being refined, free fatty acids being calculated as oleic acid in accordance with well established custom in the trade.

45 Thus if a fatty oil shows a free fatty acid content of 1% by weight, one would employ between 0.38% and 0.57% by weight based on the oil of sodium carbonate on a dry basis in an aqueous solution of at least 22° Bé.

50 For best results the soapstock at the temperature at which it is separated should be free-flowing. Appropriate conditions of fluidity are inherent in the practice of the new process.

55 The centrifugal force employed in the separation of soapstock from the refined oil is preferably at least 5000 times gravity determined at the inner periphery of the bowl at its greatest inner radius, and particularly 8000 times gravity and above. Outstanding results are obtained when the foregoing centrifugal force is at least 10,000 times gravity.

70 As indicated above it is common practice, particularly with highly colored oils, to subject the same to a second refining treatment, commonly with caustic soda, primarily

for the purpose of further reduction in color, and frequently accompanied by some further reduction in free fatty acid content.

Returning now to Figure 1 of the drawings, as shown, the refined oil leaving centrifuge 17 through line 19 is delivered to a container 22. For rerefining purposes, as illustrated, the refined oil is pumped from container 22 by pump 23 through cooler 24 wherein the temperature of the oil preferably is reduced for example to 100° F. or below. The purpose of cooling the oil at this point is to avoid contacting the oil with aqueous caustic soda at a relatively high temperature, which appears at least in some cases to fix color in the oil beyond removal. If fixing of color due to temperature does not present a problem, the cooling step may be avoided.

From cooler 24 the oil flows to mixer 25 through line 26 wherein it is mixed with aqueous caustic soda pumped from source 27 by means of proportioning pump 28. The mixture flows from mixer 25 through heater 29 wherein the temperature of the mixture is raised to say between 120° F. and 160° F., whereupon the mixture is delivered to centrifuge 30 for the separation of the oil from the reagent phase. As shown the oil flows from centrifuge 30 through line 33, and the reagent through line 34. The use of from 1% to 5% by weight based on the oil of aqueous caustic soda solution of from 8° to 30° Bé. is typical of usual operations. Any other rerefining procedure may be employed.

As pointed out above, the initial refining of the oil by the use of this invention assists in obtaining an oil of lower finished color upon rerefining, then when prior art processes are employed for such initial refining.

Also as pointed out above, additional savings in neutral oil may frequently be effected, and even better centrifugal separations of soapstock and oil from each other obtained, by venting off from the mixture of oil and reagent, after mixing but before centrifugation, at least a portion of any gaseous material that might be present. One means of accomplishing this purpose is illustrated in Figure 2 wherein the mixture of oil and reagent leaving heater 16 is conducted to container 40 having a vent 41 at the top thereof. Vent 41 may be of any desired construction capable of permitting passage therethrough of gases while preventing the passage of liquid, many different types of which are well known in the art. A typical gas vent valve is illustrated as comprising a float 42 to the upper portion of which is attached a valve stem 43 held in sliding position by a guide 44, and the upper end of which engages a valve seat 45 to close the opening therein when the float 42 is moved upwardly due to the entry of liquid into the vent 41. Movement of float 42 downward due to the accumulation of gas in vent 41 causes the valve to open to permit the escape of gas. Any other suitable device may be substituted.

The mixture of oil and reagent is fed through heater 16 and through container 40, e. g., under the pressure supplied by pumps 14 and 15 (see Figure 1), tending to keep the container 40 full of liquid in view of the operation of the vent 41. From container 40 the mixture flows to centrifuge 17, e. g., through line 47.

It will be appreciated that the mixture flowing through container 40 may be under any desired elevated pressure, and that the vent 41 will nevertheless function for the venting off of gases.

A simpler arrangement for the venting off of gases from the mixture of oil and reagent is illustrated in Figure 3 wherein the flow from heater 16 is into a container 50 having a simple vent 51 to the atmosphere.

When employing a simple vent, such as 51, it is preferred to control the amount of liquid mixture in container 50. This may be done, for example, by means of a float controlled valve 52 in exit line 59, and operated by float mechanism 53 comprising float 54, lever arm 55 and links 56 and 57. Pump 58 pumps the mixture through the valve 52, and the rate of flow through the

valve 52 is controlled by the vertical position of float 54, valve 52 being moved toward open position upon rise of the float 54 and moved toward closed position upon lowering of the float.

From container 50 the mixture is pumped to centrifuge 17, such as through line 59, and is separated in centrifuge 17 as previously described.

It will, of course, be understood that when employing the arrangement illustrated in Figure 3, the temperature of the mixture preferably should not be raised to boiling, e. g., above about 212° F., since the pressure in tank 50 is atmospheric.

While the position of the vent has been illustrated as being downstream from the heater 16, it is to be understood that, broadly speaking, the vent may be positioned at any desired point between the mixing and the centrifuging, also a plurality of vents may be employed, e. g., for the venting of gases both upstream and downstream of the heater 16.

In the industry it is customary to subject the refined oil, or, if rerefining is resorted to, the rerefined oil, to water washing to remove any possible residual soapstock and/or reagent. This is followed by drying of the oil, customarily under vacuum.

The following examples of the practice of the invention are given by way of illustration and not of limitation.

Example 1

Corn oil having a free fatty acid content of 2.0% was refined under temperature conditions between 185° F. and 205° F. with an aqueous sodium carbonate solution of 22° Bé. Four different continuous runs were made in which the amount of sodium carbonate based on the theoretical stoichiometric amount was as follows:

Run No. 1.—1.7 times the theoretical stoichiometric amount.

Run No. 2.—2.8 times the theoretical stoichiometric amount.

Run No. 3.—3.5 times the theoretical stoichiometric amount.

Run No. 4.—6.1 times the theoretical stoichiometric amount.

After centrifugal separation of the soapstock from the refined oil in each case, the oil was continuously refined under temperature conditions between 140° F. and 150° F. with 1.5% by weight based on the oil of aqueous caustic soda solution of 20° Bé. This was followed in each instance with centrifugal separation of the reagent from the oil, and then by conventional water washing of the oil with subsequent drying thereof under vacuum. The results were as follows:

Run No.:	Percent Refining Loss
1	4.28
2	3.85
3	4.07
4	5.00

Example 2

Corn oil having a free fatty acid content of 1.2% was refined in a continuous stream vented to the atmosphere and under temperature conditions between 195° F. and 200° F. with an aqueous sodium carbonate solution of 22° Bé., the ratio of said aqueous solution to the oil being such that the sodium carbonate employed was 2.9 times the theoretical stoichiometric amount. After separating the soapstock from the oil by centrifuging, the oil upon analysis showed a free fatty acid content of 0.13%. The oil was then rerefined in a continuous stream with 1.5% by weight based on the oil of aqueous caustic soda solution of 20° Bé. under temperature conditions between 130° F. and 140° F. Upon separation of the reagent from the oil by centrifuging, the oil upon analysis showed a free fatty acid content of 0.04%. The oil was then water washed and vacuum dried in a

70

conventional manner. The overall loss was 2.85% by weight based on the original oil. The "refining loss" as determined analytically, employing the applicable official method of the American Oil Chemists Society, was 5%.

Example 3

Corn oil having a free fatty acid content of 2.1% by weight was refined in a continuous stream under temperature conditions between 200° F. and 205° F. with an aqueous sodium carbonate solution of 22° Bé., the amount of sodium carbonate employed being 2.5 times the theoretical stoichiometric amount. After separation of the soapstock from the oil by centrifuging, the oil upon analysis showed a free fatty acid content of 0.08%. The separated oil was rerefined in a continuous stream at a temperature between 140° F. and 150° F. with 1.6% by weight based on the oil of an aqueous caustic soda solution of 20° Bé. After separation of the reagent from the oil by centrifuging, the oil upon analysis showed a free fatty acid content of 0.03%. The overall loss was 4.05% by weight based on the original oil. The "refining loss" as determined analytically, employing the applicable official method of the American Oil Chemists Society, was 6.8%.

Example 4

12 tank cars of a highly colored cottonseed oil having an average free fatty acid content of 1.6% by weight was refined in a continuous vented stream under temperature conditions between 200° F. and 210° F. with an aqueous sodium carbonate solution of 26° Bé. The amount of sodium carbonate employed was between 2 and 3 times the theoretical stoichiometric amount, the average being 2.1 times. After separation of the soapstock from the oil by centrifuging, the oil upon analysis showed an average free fatty acid content of 0.06%. The separated oil was rerefined in a continuous stream under temperature conditions between 155° F. and 160° F. with 3% by weight based on the oil of an aqueous caustic soda solution of 20° Bé. After separation of the reagent from the oil by centrifuging, the oil upon analysis showed an average free fatty acid content of .02%. The oil was then subjected to conventional water washing and vacuum drying. The overall loss was 6.1% by weight based on the original oil, and the final refined oil had an average bleach color of 20 yellow, and 2.4 red, which is an outstanding result since it exemplifies the refining of highly colored cottonseed oil into what is known in the trade as a prime oil, i. e., an oil having a bleach color not greater than 2.5 red, which is an extremely difficult task as exemplified by the color obtained through laboratory refining as noted below. The average laboratory "refining loss" as determined analytically, employing the applicable official method of the American Oil Chemists Society, was 8.1% by weight, and the average bleach color so determined was 20 yellow and 2.7 red. The outstanding results obtained are pointed up by the fact that it is extremely difficult in the case of a highly colored cottonseed oil to reduce the red bleach color below that obtained by the above official method.

Any other fatty oil may be substituted in the above examples with comparable results. Likewise any other temperature conditions, any other ratio of sodium carbonate to free fatty acids, any other concentration of sodium carbonate in aqueous solution, any other ratio of caustic soda to oil for rerefining, any other concentration of caustic soda in aqueous solution for refining, etc., as set forth herein and in the claims, may be substituted in the above examples with comparable results.

While the centrifugal forces used in the separations effected in the foregoing examples were between approximately 10,000 and 15,000 times gravity, lower centrifugal forces may be substituted in these examples with the unexpected results to which this invention relates. Also full bowl separation may be substituted for the

open bowl separation employed in the examples, although the open bowl separation with the atmospheric venting employed is preferred. Likewise, separation by gravity may be substituted, but with less efficient separation.

For purposes of simplicity and convenience in description, auxiliary equipment such as pumps, valves, motors, controls, thermometers, pressure gauges, strainers, flow meters and the like, have been omitted from the flow diagrams, since these items and their use in a well-designed plant will immediately occur to the skilled engineer upon becoming familiar herewith.

While specific conditions for the refining of fatty oils have been described, it is to be understood that this is by way of illustration, and that modifications may be made without departing from the spirit of the invention. Accordingly it is intended that the patent shall cover, by suitable expression in the claims, the various features of patentable novelty that reside in the invention.

We claim:

1. A process for the refining of a fatty oil containing free fatty acid which comprises combining a stream of said oil and a stream of aqueous sodium carbonate solution of at least 22° Bé. in measured quantity such that the amount based on the free fatty acids contained in said oil of sodium carbonate added to said oil is from 2 to 3 times the theoretical stoichiometric amount for said oil, venting gas from said combined streams of oil and aqueous sodium carbonate solution, thereafter and while in mixed state flowing said combined streams at a temperature of at least 180° F. to a centrifugal separator, and separating in said centrifugal separator said oil from the soapstock formed as a result of said treatment.
2. A process for the refining of a fatty oil containing free fatty acid which comprises flowing proportional quantities of said oil and of an aqueous sodium carbonate solution of at least 22° Bé. into confluence and then concurrently in a liquid stream and under temperature conditions between approximately 180° F. and 225° F. and with a removal of gas therefrom to a centrifugal separator, and separating the oil from the reagent phase in said centrifugal separator, the amount based on the free fatty acids contained in said oil of sodium carbonate added to said oil being from 2 to 3 times the theoretical stoichiometric amount for said oil.
3. The process of claim 2 in which the temperature conditions referred to are maintained between approximately 180° F. and 212° F.
4. The process of claim 2 wherein the separation takes place in a centrifugal separator having a bowl of the open type.
5. The process of claim 4 wherein the bowl is vented to the atmosphere.
6. The process of claim 2 wherein separation takes place under centrifugal forces of at least 5000 times gravity.
7. The process of claim 6 wherein separation takes place under a centrifugal force of at least 8000 times gravity.
8. The process of claim 7 wherein separation takes place under a centrifugal force of at least 10,000 times gravity.
9. The process of claim 2 wherein the final separated oil is rerefined with caustic soda to reduce color in the oil.
10. The process of claim 9 wherein the oil is a vegetable oil.
11. The process of claim 10 wherein the oil is cottonseed oil.
12. The process of claim 2 wherein the aqueous sodium carbonate solution employed is between 22° Bé. and 30° Bé.
13. The process of claim 1 in which the venting of gas from the combined streams of oil and aqueous sodium carbonate solution takes place after heating but before centrifuging.

14. A process for refining a fatty oil containing free fatty acid which comprises combining a stream of said oil and a stream of aqueous sodium carbonate solution of between 22° Bé. and 30° Bé. in measured quantity such that the amount of sodium carbonate combined with said oil is from 2 to 3 times the theoretical stoichiometric amount for neutralizing the free fatty acid contained in said oil, maintaining said combined stream under pressure conditions of at least 5 pounds per square inch, heating said combined stream to within a temperature range of from 180° F. to 212° F., venting gas from said combined stream while still under the above-mentioned temperature and pressure conditions, thereafter introducing said combined stream while still under the above-mentioned temperature conditions into a centrifugal separator **15**

operating on the open bowl principle with the bowl vented to the atmosphere, and separating in said centrifugal separator under a centrifugal force of at least 10,000 times gravity said oil from the rest of said combined stream **5** including the soapstock formed as a result of said treatment.
